UNITED STATES PATENT OFFICE.

JOHN J. SWAN, OF MONTCLAIR, NEW JERSEY.

TELEPHONE.

Application filed January 15, 1925. Serial No. 2,507.

My invention relates more particularly to a novel method and means by which the sound waves in a telephone may be confined within the transmitter and its stand, and prevented from being propagated outside of the telephone, either directly or by reflection from the diaphragm or the inner wall of the mouthpiece, thus enabling the telephone to be used without the speaker being heard by, or disturbing, others who may be in his immediate vicinity.

One object of the invention is to accomplish the above result in a practical, workable and positive manner without the use of extraneous or exterior attachments of any sort fastened to or hung upon or from the telephone mouthpiece, or the body of the transmitter or the stand.

A further object is to effect silent, or practically silent transmission of sounds and of the voice, without substantial modification of the general form and dimensions or general appearance of the standard telephone transmitter and stand.

A further object is to provide means for such secret or practically silent or disguised transmission of the voice without requiring the speaker to use an instrument that is heavy, awkward, topheavy or different in action or general appearance from that to which he is accustomed.

A further object is to provide a type of telephone which can be used in the open in offices, public places or, in general, in close proximity to other telephone instruments, or to persons, without causing disturbing noises and without others being able to understand what the speaker is saying, and without the use of telephone booths.

A still further object of the invention is to accomplish the desired results without material modification of any fundamental part of the transmitting or wiring or switching elements of the standard telephone, or the addition of any elements that will interfere with the normal functioning of the operating parts of the telephone, or involving substantial changes in design, materials, manufacture or use of the telephone or any change in its method of installation and use or objectionable effect on the general service.

The invention will be understood by reference to the accompanying drawings in which Fig. 1 is a central vertical section through the transmitter and its stand; Fig. 2 a vertical transverse section on the plane

of the line 2—2 of Fig. 1; Fig. 3 a vertical section on the plane of the line 3—3 of Fig. 1; Fig. 4 a partial section on the plane of the line 4—4 of Fig. 1; Fig. 5 a horizontal section on the plane of the line 5—5 of Fig. 1; Fig. 6 a sectional detail of the edge of the base; Fig. 7 a horizontal section on the plane of the line 7—7 of Fig. 1; Fig. 8 a view partly in vertical section and part elevation of the upper and hinge portion of stand of Fig. 1; Figs. 9, 10, 11 are part vertical mid-sections of modifications of the transmitter; Figs. 12 and 13 are perspective views of the diaphragms of Figs. 10 and 11 respectively; Fig. 14 a vertical mid-section of a modification of the base and Fig. 15 a vertical mid-section of a further modification of the transmitter. Similar reference numerals indicate similar parts in the several views.

Referring to the drawings the numeral 1 designates the casing of the transmitter within which is supported diaphragm 2 and carbon particle container 3 which is attached to a bracket piece 3^a. These parts are of the usual and well known construction. The front cover cap 4 is fitted snugly within the casing 1, and to the front is secured a mouthpiece 5. This is preferably of molded material and is little longer than the usual or standard type, being formed with side extensions 5^a to permit the outer edge to completely envelope the lips of the speaker and to be tightly closed against the face of the speaker without interfering with the movements of the lips necessary for perfect articulation.

My invention is susceptible of embodiment in various forms capable of producing the desired result, and those forms which are described herein are not to be taken as excluding others which may be found suitable. One form is illustrated in Fig. 1 wherein the cover cap 4 is formed with an inner wall in which are formed two series of openings or ports 6 and 7, as shown in Fig. 2, the former being in front of the diaphragm and the latter near the periphery of the cover exterior to the diaphragm. The two sets of ports 6 and 7 communicate with the chamber 8 in the cover, formed by the outer and inner walls, thus providing a continuous or open passageway from the mouthpiece and chamber in front of the diaphragm to the chamber 9 in the case at the rear of the diaphragm, as indicated by the continuous dotted arrows. The mouthpiece 5 as above stated, is of such de-

- sign and construction as to permit the outer edge to be completely sealed against the face of the speaker, when desired, as indicated in Fig. 1, thus insuring all of the sound produced by the speaker entering and being confined within the mouthpiece and caused to act upon the diaphragm, and then to be carried to the rear of the diaphragm, as will be later described.
- 10 In the standard form of transmitter now in use, the transmitter case is so mounted as to permit of vertical adjustment both up and down. The construction, however, provides an opening to the atmosphere, immediately 15 below the hinge, which permits the passage of the conductors to the transmitter. In the carrying out of my invention which necessitates confining the air pulsations and sound waves within the stand, I have modified the 20 present standard construction as follows:
- The top section 10 of the stand, as shown in Figs. 1, 3 and 8, is formed at its upper end as a hollow clevis or Y having openings 10^a in its inner bearing faces corresponding with 25 openings in the hinge end 11 of the case 1. A pivot pin 12 passes through the center of the hinge with bearings in the clevis and in the hinge end of the case. The openings 10^a in the upper part of the top section 10 and the 30 hinge end of the casing communicate directly with the chamber 9 in the case at the rear of the diaphragm, the inner faces of the clevis and the hinge end of the case forming a sealed joint with no opening to the atmosphere 35 whatever, as in the standard construction. No obstruction, however, is offered to the passage of the conductors 13, from the switch terminals and strap sections 14 and 15, to the transmitter.
- 40 The lower end of the section 10 is supported and sealed in any suitable way in the main tube 16 of the stand, the latter in turn being supported upon the base shell 17 by means of a screw collar 18 according to 45 standard practice. As shown in Figs. 1, 5 and 8, the strap 14 is secured by screws 19 to the lower portion of section 10. Through the opening in the bottom plate 20 of the base extends a screw 21 which engages the flange 22 50 at the lower end of the strap 14. By tightening screw 21 the shoulder 10^b of section 10 is clamped securely against the upper edge of the tube 16, thus securely locking together and sealing the section 10, tube 16, and the 55 base plate 20, and thereby constituting a continuous closed chamber or passage from the mouthpiece to the base without interference with any of the mechanical or electrical features essential to the operation of the telephone, and irrespective of any adjusted position of the transmitter case. To prevent the building up of air pressure within such closed chamber, when the mouthpiece is held 60 closed by the speaker, by permitting the escape of air pulsations, I form openings 23 in the upturned flanged edge of the base plate 20, and also openings 23^a in the ring 24 which is used to clamp and hold in place the felt bottom cover 25. Ring 24 also constitutes a 65 guide for the base shell 17.
- 70 From the foregoing description it is obvious that with the speaker's face closed against the mouthpiece the air impulses produced in speaking, travel a free and unimpeded passage from the mouthpiece 5 to the diaphragm 2, thence around the exterior of the diaphragm into the enclosed chamber 9, through the hinge and down through the stand to the base and out through the openings in the outer periphery of the base, as 80 shown by continuous dotted arrows, thus making possible the speaker closing his face tightly against the mouthpiece and breathing or speaking freely and in normal manner into the telephone without interference with 85 articulation, breathing or the normal operation of the transmitter, or the switching and other mechanism within the telephone, which cannot be done in any present forms of telephone transmitters of which I have knowledge.
- 90 While the air pulsations are thus permitted to pass through the closed space provided by the transmitter case, stand and base, as indicated by the arrows in Figs. 1 and 7, it is necessary to the carrying out of my invention 95 that the intensity of the sound waves be so diminished that they cease to be audible, or muffled or deadened within this space after they have acted upon the diaphragm. The 100 desired muffling or deadening of the sound waves may be wholly or partially effected by the mere provision of the described closed space provided by the transmitter case, stand and base. As, however, a given telephone 105 may be used by many different persons the intensity of the sounds is not uniform. To assure the desired result of sound muffling under all conditions of use, I introduce either 110 in the transmitter case, stand or base, mechanical means which absorb or prevent the transmission of the sound waves beyond the base. It is not of the essence of my invention where the absorbing or muffling means is located, provided such means function after 115 the sound waves have acted upon the diaphragm and are then permitted to propagate in the air confined within the transmitter case and stand until they are muffled or diminished so as to be practically inaudible. Nor is the form of the muffling or dampening 120 means of the essence of my invention, as the form may be varied within relatively wide limits. One simple means is illustrated in the drawings by lining the walls of the case, stand and base with felt, cloth, rubber, or any fibrous or other material substantially 125 impervious to sound transmission. This lining is indicated by the numeral 26 in the several drawings. To still further insure, if 130

necessary, the muffling or silencing of the sound waves I may, as indicated in Figs. 1 and 7 introduce partitions 27 and 28 formed of felt, or any other pervious material permitting the passage of air, but impervious or deadening to sound waves. These partitions may be conveniently formed as concentric cylinders, labyrinths, spirals or convolutions of other sorts. There may be any desired number, two being illustrated. These partitions, as shown in Figs. 1 and 6, are supported by a perforated flanged plate 29 which may be covered with a felt or other air-pervious but sound-absorbing material 30. Also, if desired, an additional air-pervious sheet or disk may be introduced between the flanged plate 29 and the base plate 20. Although I have shown these air-pervious but sound-deadening cylinders, linings and disks, it is not absolutely essential to the successful operation of my invention that they all be used in the exact form or manner shown, it being obvious that these parts may be variously arranged and disposed within the chamber leading from the mouthpiece to the base. I have illustrated one modification of the disposition of the sound absorbing or deadening means in Fig. 9 in which the cover of the transmitter is provided structurally with a separate cap 31 extending forward and providing a larger chamber in front of the diaphragm than that illustrated, in Fig. 1. In this chamber is placed soft felt, fibrous material, sponge rubber, or layers of material pervious to air and deadening to sound waves, vanes or a labyrinth construction causing the sound waves to travel some distance before being released into the chamber 9 at the rear of the diaphragm, and the continuous passage formed by the stand and base, as heretofore described.

Still another form of sound deadening means is illustrated in Fig. 14, which may be used either alone or in combination with the other means described and consists, as shown, of a mass of sponge rubber, or a fibrous material 33, substantially solid but pervious to air, permitting the outward passage of air pulsations to prevent the building up of pressure, and cause the deadening of the sound waves and also conversely permit the inhalation of air if the speaker is breathing with the mouthpiece close to the face. To completely seal the base except for the openings 23 the opening for the incoming wires 34 is sealed by a bushing 35, or other means.

Instead of providing escape ports 6 and 7 in the cap 4 for the air pulsations and sound waves, I may make the cap of standard design, as shown in Figs. 10 and 11, and perforate the diaphragm 2^a near its periphery with a series of openings 36, or I may locate the perforations 37 in the flange 26 as shown in Figs. 11 and 13. In both of these latter

forms the air pulsations and sound waves are conducted away continuously as emitted by the speaker without being reflected back into the mouthpiece, in substantially the same way as in the construction illustrated in Figs. 70 and 9.

In the present standard design of telephone stand the receiver hook extends through a slot in the stand tube 16. In carrying out my invention it is desirable that this slot be closed in order to avoid any opening to the atmosphere through which the sound waves might pass before being muffled. The closure of this slot in tube 16 may be effected in various ways, one means being illustrated in Fig. 8. As there shown, the switch strap 14 is drilled to receive a screw 38 which is tapped into the stop lug 39^a of the receiver hook 39. This locks the receiver hook in fixed down position so that it does not function as in the standard telephone when the receiver 40 (shown in dotted lines) is removed, the receiver itself, in my construction, being utilized to open and close the switch. In the drawing the receiver is assumed to be removed from the hook, the dotted line merely indicating the position of the receiver when placed on the hook.

When the receiver 40 is on the hook 34 it presses against the button 41 on a free moving member 42, the other end of which bears against the regular switch-actuating spring 43, causing it to move backward to permit the opening of the spring contacts 15. When the receiver is removed, the spring 43 moves the member 42, thereby permitting the spring to close the contacts 15. 44 is an insulated button of the usual type on the inner end of the member 42. There being no movement of the hook itself there is no necessity for the usual slot in the standard design of stand. In order, however, that the general design may be maintained and use be made of existing stand sections, as far as possible, the slot therein may be closed by a plate 45, curved to fit tightly the exterior of tube 16 and to straddle the receiver hook 29. This construction permits the ready removal of all of the parts contained within the tube 16, just as at present, by removing the screw 21, shown in Figs. 1 and 14.

From the foregoing description it will be seen that when the user of the telephone desires to carry on a silent conversation, he closes the outer end of the mouthpiece by pressing it firmly against his face, as indicated in Fig. 1, the design of the mouthpiece being such that when so closed it does not interfere either with the articulation, enunciation or breathing of the speaker. When so closed, all of the sound waves are confined within and are concentrated, by reason of the conical shape of the mouthpiece, directly against the diaphragm. As the mouthpiece is closed to the atmosphere at its outer end

the sound waves set in vibration by the speaker are permitted to continue their travel, after acting upon the diaphragm, through the open ports either in the transmitter cover, or 5 in the diaphragm, into the chamber 9 at the rear of the diaphragm. This chamber is of relatively greater volume than the volume of the ports so that there is effected in such enlarged chamber a partial muffling or silencing 10 of the sound waves. They then travel directly into and through the narrower passage of the clevis and stand until finally they meet the sound absorbing chamber in the base where they are muffled or deadened so as to 15 be substantially inaudible or indistinguishable. The general course of the sound waves through the closed space provided in the case, stand and base, is indicated by the dotted arrows in Fig. 1.

20 During the time that the user is carrying on a conversation, either speaking himself or listening through the receiver, he may maintain the position indicated in Fig. 1 without interfering with normal respiration through 25 the nostrils or the mouth. As he speaks into the mouthpiece the air pulsations from the lungs do not build up pressure either in the mouthpiece, the transmitter casing or the stand, as there is a sufficiently free outlet for 30 the exhaled air from the mouthpiece through the open ports of the casing, the stand and the openings in the base. This enables a substantially balanced air pressure to be maintained on both sides of the diaphragm which 35 does not disturb the normal operation of the diaphragm. The maintenance of this condition involves a proper relation between the cross-sectional areas of the outlet ports leading from the front to the rear of the diaphragm, and the amount, character and dis- 40 position of the sound absorbing material in the stand or its base. Such material is prefer- ably located in the base as the latter affords ample space for its disposition, that is, the 45 amount and arrangement of the sound absorbing material should be such as to effect the main purpose which is the effective deadening or muffling of the sound waves, without preventing the free escape of the air from the 50 speaker's lungs in order to avoid building up a degree of back pressure of air which would interfere with the free and normal action of the diaphragm.

55 Thus two main factors enter into the practical application of my invention, namely, the deadening or muffling of the sound waves within the transmitter casing and the stand, and the provision of means to prevent the building up of a back pressure at the rear of 60 the diaphragm. The former object is attained by providing a path or conduit for the sound waves other than by reflecting them back from the diaphragm into the mouthpiece, that is, by permitting them to be prop- 65 agated through the air contained within the

casing and stand from the space in front of the diaphragm to the chamber at the rear thereof, and thence onward until muffled or deadened. The second factor is taken care of by the openings to the atmosphere in the 70 base beyond the sound absorbing means. The building up of a substantial or non-desirable air pressure within the casing and stand is ob- viated because the sound deadening means, even if of felt or cloth, is pervious to air in 75 both directions.

Should, however, conditions arise in the use of my invention making it desirable to maintain actual atmospheric or exterior air pressure directly on the rear face of the diaphragm entirely independent of and isolat- 80 ed from the pressure or air and sound vibrations in chamber 9, or the pressure and sound in the closed mouthpiece and chamber in front of the diaphragm, I employ a substan- tial or practically rigid partition 46 to close the recess in the cap or cover 4 behind the diaphragm 2. This is sealed around its outer edge and is sealed where the fixed portion of the carbon particle container 3 enters through 85 its center portion. In this way I form an air tight compartment 47 directly behind the diaphragm. Free access of atmospheric or outside pressure from this chamber is ef- fected by means of a vent hole 48 through the 90 cover 4. Partition 46 may, if desired, serve as the support of part 3 thereby making the bracket 3^a unnecessary.

While I have shown my invention as applied to the desk type of telephone with sep- 100 arate receiver and stand, it is to be under- stood that the invention is applicable to other types such as that in which the trans- mitter and receiver are mounted on a common stand or frame and adapted to be held by the 105 hand against the mouth and ear, and to the automatic pay telephones in which the trans- mitter case is attached to the front of the coin box. The term "stand" as used by me is therefore to be taken as meaning any form 110 or type of support for the transmitter, and adapted to effect the confining of the sound waves within the telephone instrument and the muffling, neutralizing, absorbing or inter- 115 ference of the sound waves after they have acted upon the diaphragm in the usual or nor- mal manner. In other words, to deaden the sound waves so that there shall be no propa- gation of such waves through the openings in 120 the transmitter stand which openings are necessary to permit the escape of the air pul- 125 sations or pumping effects produced by the speaker when using the telephone in the manner described, that is, with his face pressed against and closing the outer end of the mouthpiece.

What I claim is:—

1. A telephone transmitter comprising a 130 casing, a diaphragm supported therein, and forming two distinct compartments, and

means to confine and conduct the air pulsations and sound waves around the diaphragm from the front compartment to the rear compartment, and means to prevent accumulated 5 or excessive air pressure in the rear chamber or passage at the rear of the diaphragm due to the air impulses produced by the speaker.

2. A telephone transmitter comprising a casing having a cap, a diaphragm supported 10 therein, forming front and rear compartments, means to conduct the sound waves that enter the front chamber, after they have acted upon the front of the diaphragm, into and through the second chamber or passage to 15 diminish their intensity so that they cease to be audible, or become indistinguishable.

3. A telephone transmitter comprising a casing having a cap, a diaphragm supported within the casing, a mouthpiece attached to 20 the cap and adapted to be closed at its free end by the face of the speaker, and means to cause the air pulsations and sound waves after acting upon the front of the diaphragm, to be conveyed continuously beyond and away from 25 the rear of the diaphragm, in volume such as to avoid building up of pressure at the rear of the diaphragm to act on the rear or back thereof.

4. A telephone transmitter comprising a 30 casing having a cap, a diaphragm supported within the casing, a mouthpiece attached to the cap and adapted to be entirely closed at its free end by the face of the speaker, and means for confining the air pulsations and 35 sound waves within the casing and stand, when the free or open end of the mouthpiece is closed by the face of the speaker, and to conduct the air pulsations to escape from the casing and stand in volume sufficient to prevent 40 action on the back of the diaphragm.

5. A telephone transmitter comprising a 45 casing having a diaphragm supported therein, a hollow support for said casing, and means to conduct the propagation of all of the sound waves, after they have acted upon the front of the diaphragm, from the front to the rear of the diaphragm and through the support, and a sound muffling device within said support.

50 6. A telephone transmitter comprising a casing having a cap, a diaphragm supported thereby, a mouthpiece attached to the cap and adapted to be entirely closed at its free end by

the face of the speaker, means to conduct all the air pulsations and sound waves after acting upon the front of the diaphragm beyond 55 and away from the rear of the diaphragm, and means to prevent such air impulses and sound vibrations from direct contact with the back of the diaphragm while flowing through 60 the casing.

7. A telephone transmitter comprising a casing having a cap, a diaphragm supported thereby, a partition within the casing at the rear of the diaphragm, said partition and the 65 diaphragm forming the walls of a closed chamber, the casing having a vent from such chamber to the atmosphere, a mouthpiece attached to the cap adapted to be entirely closed at its free end by the face of the speaker, and 70 means to cause all the air impulses and sound waves after acting upon the front of the diaphragm to be conveyed beyond the diaphragm and chamber closing partition within the casing, without direct action on the rear of the 75 diaphragm, and means within the transmitter casing, for diminishing or neutralizing the sound waves.

8. A telephone transmitter comprising a 80 casing having a cap, a diaphragm supported thereby, a partition within the casing at the rear of the diaphragm, said partition and the diaphragm forming the walls of a closed chamber, the casing having a vent from such chamber to the atmosphere, a mouthpiece attached to the cap adapted to be closed at its free end by the face of the speaker, and means to cause the air impulses and sound waves 85 after acting upon the diaphragm to be conveyed beyond the diaphragm and chamber closing partition within the casing, without direct action on the rear of the diaphragm. 90

9. A telephone transmitter comprising a hollow casing having at one end a base and at the other a mouth piece jointed to the casing and forming a continuation of the cavity thereof, a diaphragm transverse to the casing, the casing having means to conduct air pulsations and sound waves around the diaphragm, said base having openings for the escape of air, and muffling devices in the casing previous to air to enable the escape thereof at the openings of the base.

In witness whereof I have hereunto signed my name.

JOHN J. SWAN.
